[57] CLAIM

The ornamental design for a valve handle cover, as shown and described.

DESCRIPTION

FIG. 1 is a perspective view of a valve handle cover showing the upper surfaces of my new design;

FIG. 2 is a perspective view of a valve handle cover showing the lower surfaces of my new design;

FIG. 3 is a top plan thereof;

FIG. 4 is a side elevation of a valve handle cover, typical of a side elevation from all sides;

FIG. 5 is a bottom plan thereof;

FIG. 6 is a perspective view of a second embodiment of a valve handle cover showing the upper surfaces of my new design;

FIG. 7 is a perspective view of a valve handle cover showing the lower surfaces of my new design;

FIG. 8 is a top plan thereof;

FIG. 9 is a side elevation of a valve handle cover, typical of a side elevation from all sides; and,

FIG. 10 is a bottom plan thereof.
